UNITED STATES PATENT OFFICE.

JOHN A. FANGER, OF KALIDA, OHIO.

BEET-HARVESTER.

1,072,218.

Specification of Letters Patent. Patented Sept. 2, 1913.

Application filed August 27, 1912. Serial No. 717,329.

To all whom it may concern:

Be it known that I, JOHN A. FANGER, a citizen of the United States, residing at Kalida, in the county of Putnam and State 5 of Ohio, have invented new and useful Improvements in Beet-Harvesters, of which the following is a specification.

This invention relates to beet harvesters, and it has particular reference to organized 10 machines of this class which are utilized for lifting the beets from the ground, topping the same and conveying the topped beets to a receptacle, such as the box or body of a wagon accompanying the har- 15 vester.

The principal object of the present invention is to produce simple and improved mechanism for lifting the beet and for topping the same, said mechanism being constructed and mounted in such a manner as 20 to be capable of being effectively utilized for the purpose desired.

A further object of the invention is to simplify and improve the general construction and assemblage of parts constituting 25 the improved machine.

With these and other ends in view which will readily appear as the nature of the invention is better understood, the same consists in the improved construction and novel 30 arrangement and combination of parts which will be hereinafter fully described and particularly pointed out in the claims.

In the accompanying drawings has been 35 illustrated a simple and preferred form of the invention, it being, however, understood that no limitation is necessarily made to the precise structural details therein exhibited, but that changes, alterations and 40 modifications within the scope of the claims may be resorted to when desired.

In the drawings, Figure 1 is a top plan view of a machine constructed in accordance with the invention. Fig. 2 is a side elevation, partly in section of the improved machine. Fig. 3 is a longitudinal sectional view taken on the line 3—3 in Fig. 1. Fig. 4 is a sectional detail view taken on the line 4—4 in Fig. 3. Fig. 5 is a transverse sectional view taken on the line 5—5 in Fig. 1. Fig. 6 is a transverse sectional view taken on the line 6—6 in Fig. 1. Fig. 7 is a sectional detail view, taken on the line 7—7 in Fig. 4, and showing a beet in position to 55 be topped. Fig. 8 is a sectional view taken on the line 8—8 in Fig. 3. Fig. 9 is a de-

tail plan view of a portion of the link belt. Fig. 10 is a sectional detail view taken on the line 10—10 in Fig. 3.

Corresponding parts in the several figures are denoted by like characters of reference.

The frame A of the improved machine is supported on front and rear axles 15, 16, bolsters 17, 18 being utilized to raise 60 the frame to the desired height. The front axle is provided with steering wheels 19, the same being journaled on spindles 20 which are connected with the axle by knuckle joints 21, said spindles being provided with forwardly extending arms 22 which are connected by means of links 23 with a suitably supported rack bar 24, said rack bar being engaged by a pinion 25 mounted on a steering rod 26 having a hand 70 wheel 27 which constitutes the steering wheel and which is located in convenient proximity to the driver whose seat 28 is suitably supported on the frame.

Pivotedly supported on the rear axle 16 is a frame or casing B which supports and contains the principal operating parts or members of the improved device. Each of the side members 29 of the casing B has on its inner face and adjacent to its lower edge 80 a housing 30, adjacent to the front end of which is mounted a digger blade 31, said digger blades being of wedge or chisel-shape so as to dig into the ground in a manner which will be readily understood, the two 85 blades coöperating to engage a beet root which by the joint action of said blades will be lifted over their inclined surfaces and thus partly extracted from the ground. The side members 29 are provided at their 90 front edges with cheek plates 32 constituting right and left mold boards by the action of which a considerable portion of the dirt excavated by the diggers will be moved laterally out of the way.

Supported for rotation in the housings 30 are right and left screw conveyers 33, the journals at the rear ends of which 34 are provided with bevel pinions 35. Motion is transmitted to the screw conveyers by means 100 to be hereinafter described, whereby said conveyers are positively driven. The screw conveyers 33 are tapered in a forward direction to admit of the ready entrance of a beet root therebetween, the function of said 105 screws being to elevate or extract the beet gradually from the ground, and the screw 110

conveyers being with this end in view supported in an inclined position, as shown. The frame or casing B is provided near its front end with arms or brackets 36 with which is pivotally connected a yoke 37, with which the lower end of a screw threaded rod 38 is connected. The upwardly extended end of said rod is guided through an upright frame 39, and said screw threaded rod is provided with an internally threaded sleeve or nut 40 having a bevel gear 41, the same being supported on a cross bar 42 of the frame 39. A shaft 43 which is supported for rotation in one side member of the frame 39 carries at one end a bevel pinion 44 meshing with the bevel gear 41, and at the other end a crank 45, whereby it may be rotated for the purpose of rotating the sleeve or nut 40, thereby raising or lowering the front end of the frame or casing B. It will be seen that by this simple means, the front end of the frame may be raised above or lowered into engagement with the ground; the depth of operation of the blades or diggers may be gaged and regulated, and the screw conveyers will be maintained at the proper inclination.

Pivotedly supported near the front end of the frame or casing B, on the side members 30 of said casing, are arms 47 carrying a suitably supported roller 48 which is pressed in a forward direction by the action of springs 49 which may be arranged in any suitable manner to exert tension against the 35 journals or bearings of the roller. Stops 50, 51, best seen in Fig. 2, are provided to limit the upward and downward movement of the pivoted roller carrying arms. A shaft 52 which is supported for rotation in the side 40 members of the frame B near the rear end of the latter is provided with sprocket wheels 53. A link belt 54 is guided over the sprocket wheels 53 and over the roller 48, said link belt constituting an endless 45 conveyer. The upper lead of said conveyer is deflected upwardly and guided over rollers 55 on rods 56, said rollers and rods serving also to connect and to space the side members of the frame. The link belt 54 is 50 preferably constructed in such a manner as to be flexible transversely as well as longitudinally, and with this end in view the belt is preferably composed of flexibly connected links placed side by side, as well as end to 55 end, as will be clearly seen in Fig. 9 of the drawings. It is desired to be understood, however, that no limitation is intended to be made to the special form of link belt shown in this figure, as a flexible endless conveyer 60 of leather or textile material and of any suitable construction may be used. A form of link belt as illustrated in Fig. 9 is, however, deemed particularly serviceable in this machine, since when subjected to the pressure 65 of a beet, it will have a tendency to be-

come cupped around the head of the beet root which will thus be gripped and positively conveyed or carried in a very positive and satisfactory manner.

The conveyer or link belt is provided at suitable intervals with teeth or prongs 57 which will penetrate the tops of the beet roots and assist in positively carrying the same as well as in holding such roots nearly upright while being conveyed in a rearward direction. 75

The side members 29 of the casing B are provided each with a plurality of slots 58 wherein are fitted slidable bearing members 59 supporting the journals of rollers 60 that extend transversely through the casing. The bearing members 59 are provided with upwardly extending rods 61 guided through flanges 62 on the side members of the casing, said bearing members being forced downwardly in the direction of the lower ends of the slots 58 by the action of springs 63 that are coiled about the rods 61 between the bearing members and the flanges. The rollers 60 are positioned above the lower lead of the conveyer 54, and the rollers 55 over which the upper lead of said conveyer is deflected and guided are preferably positioned above the upper ends of the slots 58, as will be clearly seen in Fig. 3, thus keeping said upper lead entirely out of the path of the rollers 60 when the latter are forced upwardly during the operation of the machine, as will presently appear. 90

The side members 29 of the casing B are provided on their inner faces with grooves or recesses 64 to accommodate the cheeks or side members 65 of the knife carrier 66 which is slidably mounted in said grooves or recesses. The carrier, which supports the knife or cutter 67 for topping the beets, is provided with a cross bar 68 extending transversely across the front portion of the topping knife, said cross bar being rounded on its underside so as to present no obstruction to the passage of the conveyer 54. The knife carrier is also provided on its upper side with longitudinally disposed flanges 69 over which the lower lead of the conveyer 54 is guided, said flanges being sufficiently spaced apart to admit between them the teeth or prongs 57 which are mounted only on the central portion of the link belt or conveyer where they will be sure to engage the beet roots. The guide flanges 69 are sufficiently high to carry the teeth 57 over the knife and the knife carrier without contacting therewith. It will be noticed particularly with reference to Fig. 3 that the knife carrier is positioned directly over the rear ends of the spiral conveyer rolls 33, and that the rollers 60 extend transversely across the greater portion of the length of said spiral rolls. 110

Hingedly connected with the knife car- 130

rier, at the rear edge thereof, is an apron 70 that extends rearwardly to the tail end of the machine and over which the beet tops are dragged or guided until they are permitted to drop upon the ground over the rear edge of said apron. The latter is loosely supported, intermediate its front and rear ends on a cross bar 71.

Supported transversely below the frame 10 of the machine, in front of the rear wheels and in rear of and directly below the topping knife is a conveyer trough or casing 72, at the ends of which are supported rollers 73 over which an endless conveyer 74 is 15 guided. Hingedly connected with the ends of the trough 72 are elevator casings 75 at the ends of which are supported rollers 76 over which conveyers 77 are guided. The free ends of the elevator prongs are 20 supported by braces 78 connected with the frame of the machine.

One of the hind wheels 79 of the machine has a clutch member 80 adapted to engage a clutch member 81 formed on the hub of a 25 sprocket wheel 82 which is slidably mounted on the rear axle, said sprocket wheel being normally forced in the direction of the clutch member 80 by the action of a suitable spring 83, thereby causing the clutch members 81 and 82 to be normally held in engagement with each other, and thus causing the sprocket wheel 82 to be rotated by the wheel 79 when the machine is in operation. A shipping lever 84 is provided whereby 30 the clutch may be thrown out of gear when desired. 85 is a counter shaft having a sprocket wheel 86 which is connected with the sprocket wheel 82 by a chain 87. Loosely mounted on the counter shaft 85 are bevel 40 pinions 88, 88', either one of which may be engaged by a clutch member 89 actuated by a hand lever 90 for the purpose of transmitting rotary motion in either direction to a bevel gear 91 on a longitudinal shaft 92. 45 It will be understood that suitable means may be employed for the purpose of locking the hand lever 90 in adjusted position, thus permitting the clutch 89 to be held in engagement with either one of the wheels 88, 88', or in an intermediate idle position, and thus enabling rotary motion in any desired direction to be transmitted to the shaft 92, and enabling said shaft to remain stationary when desired. For the purpose of 55 actuating the shipping lever 84 a rock shaft 93 is provided, said rock shaft having at one end a crank 94 connected with the shipping lever and at the other end a handle 95 whereby it may be actuated.

60 The counter shaft 85 carries a sprocket wheel 96 which is connected by a chain 97 with a sprocket wheel 98 on a shaft 99 which is supported near the lower rear corner of the casing B and from which motion 65 is transmitted by a chain 100 to the shaft 52

whereby the conveyer or link belt 54 is driven. The shaft 99 also transmits motion by chains 101 to stub shafts 102 journaled in the side members 29 of the casing B, and having bevel gears 103 meshing with the 70 bevel pinions 35 on the journals of the spiral rolls 33 which are thus driven. It may be noted that the said rolls 33 must be timed to operate at proper speed with respect to the conveyer or link belt 54 so that during each 75 rotation of the rolls the conveyer will travel a distance equal to the distance between two proximate convolutions of the spiral thread of said rolls, thus causing the beet root engaged by the rolls to be moved upwardly 80 and rearwardly by the conjoint action of the rolls and the conveyer. Motion is transmitted to the conveyers 74 and 77 from the longitudinal shaft 92 by means of suitable chain gearing 104 which need not be described in detail; it being understood, however, that the direction of movement of the conveyers may be reversed by means of the clutch 89 operated by the lever 90 which governs the direction of rotation of the 90 shaft 92. A clearing roller or cylinder 105 having teeth or spikes 106 is supported in the frame or casing B directly in rear of the shaft 52 from which it receives motion by means of a chain 107.

From the foregoing description, taken in connection with the drawings hereto annexed, the operation and advantages of the improved machine will be readily understood by those skilled in the art to which it 100 appertains. As the machine advances over the field, the row of beets is straddled thereby, and the beet roots will be engaged by the diggers 31 which enter the ground beneath the large portion of the root, causing the latter to be bodily lifted over the inclined planes of the diggers, the surplus dirt excavated by said diggers being disposed of laterally by the mold boards 32. The beet root is presently engaged by the spirally grooved rolls 33 which, being supported in an upwardly and rearwardly inclined position will tend to lift and extract the beet from the ground without bruising the same. At the same time the top of the beet becomes engaged by one of the teeth 57 of the link belt or conveyer 54 which serves to move the beet in a rearward direction, the flexible nature of said link belt or conveyer causing it to become cupped around the top of the beet root. The upward pressure of the beet root will deflect the lower lead of the link belt or conveyer in an upward direction when it becomes subject to the pressure of the rollers 60, whereby the beet root will be maintained firmly seated upon the spiral rolls 33 while traveling in an upward and rearward direction. As the beet root approaches the topping knife, the upward pressure of the lower lead of the conveyer 115 120 125 130

54 will exert an upward pressure on the cross bar 68 of the knife carrier, thereby causing the topping knife to be moved upwardly to the proper position for topping 5 the beet, the topping operation being performed while the beet root is still firmly seated and supported upon the spiral rolls. As soon as the top has been removed the beet root, leaving the rolls 33, will drop 10 into the conveyer trough 72, passing from thence to one of the elevators at either side of the machine, according to the direction in which the shaft 92 that actuates the conveying mechanism is being rotated. The 15 tops are dragged rearwardly over the apron 70 which, being connected with the knife carrier, will adapt itself to any position of the latter, and the tops are eventually discharged over the rear edge of said apron 20 by the action of the spiked clearing roll or cylinder 105.

As will be seen from the foregoing, the improved beet harvester is simple in construction, and it contains few parts that require to be attended to and manipulated by the operator, the machine being essentially automatic in its operation.

While a machine has been shown adapted to operate on a single row of beets only, it 30 is to be understood that a machine may be readily constructed, embodying the principles of the invention that will be adapted to operate simultaneously on two or more rows.

35 For the purpose of disposing of the surplus dirt excavated by the machine, scrapers 109 have been provided that will serve to return the dirt to the furrow from which it has been excavated, thus preventing the 40 topped beets from dropping into the furrow.

Having thus described the invention, what is claimed as new, is:—

1. In a beet harvester, an adjustably supported casing having side members, twin 45 augers supported for rotation in the casing, an endless conveyer supported in the casing with its lower lead spaced above and co-operating with the augers, and resiliently supported rollers mounted between the leads 50 of the endless conveyer and operating downwardly with respect to the lower lead of the conveyer.

2. In a beet harvester, a pivotally and adjustably supported casing having side members, twin augers supported for rotation in the casing, diggers associated with the side members of the casing, an endless conveyer supported in the casing with its lower lead spaced above and co-operating with the 55 augers, resiliently supported rollers mount-

ed above the lower lead of the conveyer, a 65 knife carrier supported for slidable movement substantially at right angles to the endless conveyer and having a cross bar positioned above the lower lead of the conveyer, and a topping knife supported by the carrier and positioned below the lower lead of the conveyer.

3. In a beet harvester, an adjustably supported casing, means including an endless 70 conveyer for carrying beet roots lengthwise therethrough, said endless conveyer being provided at intervals with teeth to engage the tops of the beet roots, a slidably supported knife carrier having a cross bar positioned above the lower lead of the conveyer, a topping knife supported by the carrier and positioned below the lower lead of the conveyer, and guide flanges on the knife carrier to support the lower lead of the conveyer with the teeth thereof spaced above the knife carrier.

4. In a beet harvester, a pivotally and adjustably supported casing, means including an endless flexible conveyer for conveying 85 beet roots therethrough, a slidably supported spring actuated knife carrier having a cross bar positioned above and transversely across the lower lead of the endless conveyer, an apron connected hingedly with the 90 knife carrier, and extending rearwardly beneath the lower conveyer lead, and means for supporting the apron intermediate its front and rear ends.

5. In a beet harvester, an adjustably supported casing having side members, diggers associated with the side members, arms connected pivotally with the side members and extending forwardly thereof, a spring 95 pressed roller supported by said arms, twin 100 augers supported adjacent to the inner faces of the side members of the casing, an endless flexible conveyer extending lengthwise through the casing and guided over the spring pressed roller, driven rotary supporting means at the rear end of the casing over which the conveyer is guided, a knife carrier slidably supported upon the casing and having a cross bar positioned between the leads of the endless carrier, a topping knife 110 supported by the carrier above the rear ends of the twin augers, and means for driving the conveyer and the twin augers.

In testimony whereof I affix my signature in presence of two witnesses.

JOHN A. FANGER.
